Inventor.

Charles M. Greising,
By Chas. E. Lord
Atty.

UNITED STATES PATENT OFFICE.

CHARLES M. GREISING, OF ST. PAUL, MINNESOTA, ASSIGNOR TO ST. PAUL TWINE COMPANY, A CORPORATION OF MINNESOTA.

APPARATUS FOR REMOVING DUST.

1,174,065.

Specification of Letters Patent.

Patented Mar. 7, 1916.

Application filed October 9, 1913. Serial No. 794,256.

To all whom it may concern:

Be it known that I, CHARLES M. GREISING, a citizen of the United States, residing at St. Paul, in the county of Ramsey and State of Minnesota, have invented certain new and useful Improvements in Apparatus for Removing Dust, of which the following is a full, clear, and exact specification.

This invention relates to systems for removing dust from and for purifying air, and more particularly to standards or tables, upon which dust laden material is handled, forming a part of such systems through which dust is carried away from the surrounding air.

In factories where twine is manufactured a great deal of dust from the fiber or material from which twine is made is liberated. This dust permeates the air, making working conditions in such factories not only undesirable but injurious to health.

It, therefore, is the object of this invention to remove dust from the materials handled in such factories and to purify the air. This object is accomplished by providing in a dust removing or air purifying system suitable standards or tables upon which dust laden material is handled, and means for conveying away the dust.

This invention is illustrated on the accompanying sheet of drawings, in which—

Figure 1 is a dust removing and air purifying system embodying my invention; Fig. 2 is a side elevation of my dust removing standard or table forming a part of the invention; Fig. 3 is a plan view of the same; and Fig. 4 is an enlarged fragmentary sectional view of the same standard or table showing more in detail the structural arrangement of the same.

The various novel features of my invention will be apparent from the description and drawings and will be particularly pointed out in the appended claims.

By referring particularly to Fig. 1 a partial layout of a twine manufacturing plant is seen, in which are shown two machines 10 through which fiber or other material from which twine is made passes. Preparatory to passing through machines 10, the fiber is placed upon standards or tables 11, where the fiber is spread and then fed into the machines. Such fiber or material from which twine is made contains a great deal of dust which is liberated when

the fiber is handled. In factories where special precaution is not taken this dust fills the air and has proved to be of great annoyance. In order to remove the dust from the fiber and from the air generally, when the fiber is first handled, preparatory to its being fed into machines 10, I have provided the tables 11 which have a perforated top 12 and perforated sides 13. The table is provided with funnel shaped members 14, 65 preferably of sheet metal, which lead from the upper perforated portions of the table. These funnel shaped portions 14 each lead to a central conduit 15, from which a pipe 16 leads to a main suction pipe 17 connected 70 with an exhaust fan (not shown). The under part of the table 11 is formed with other funnel shaped portions 18, each of which also leads to its corresponding central conduit 15, each of the large ends of the 75 funnel shaped members 18 being provided with a screen or perforated member 18a. It is apparent, therefore, that due to the suction of a fan, the suction being effective through the pipes 17 and 16, any dust laden 80 material which is handled on the tables 11 will have the dust drawn therefrom and carried away through the exhaust system. Not only will the dust be carried away from material directly on top of the table, but 85 any dust which surrounds the table will be drawn through the side portions 13 thereof. Also any dust which has reached the floor will be drawn through the funnel shaped 90 portions 18 of the table.

To further purify the air and to remove any remaining dust which may be in the fiber after it has passed from the tables 11 into machines 10, such remaining dust will be drawn up through hoods 19 located over the machines and connected to the main exhaust pipe 17 through which dust is carried.

The table itself includes a skeleton structure, preferably of metal, comprising four 100 relatively long angle iron side strips 20 connected longitudinally by similar shorter strips 21 and six legs 22 for supporting the main body of the table.

By referring to Fig. 4 it will be noted 105 that the perforated top 12 is drawn over the edges of the side members and clamped in a fixed position by a metal strip 23 passing around the periphery of the table and screws 24 passing through said strip 23 and 110

side members. In one side of the upper body portion of the table are two doors 25 slidably mounted in channel portions 26 formed by bending side portions of the table. These slides 25 are located opposite the funnel portions 14 and are for the purpose of rendering it possible to remove any material from the funnels and conduit 15 which may tend to clog the passageways thereof. By means of this system it is possible to remove the dust from material handled in twine mills and to maintain the air in a pure condition, thus avoiding any serious results which might otherwise be occasioned.

There may be various modifications of my invention as herein particularly described,

and it is my intention to cover all such modifications which do not involve a departure from the spirit and scope of the invention as set forth in the following claim. 20

What I claim as my invention and desire to secure by Letters Patent is:

A table for handling dust laden material having top and side perforated portions, 25 and means for exhausting air through said portions.

In testimony whereof I affix my signature, in the presence of two witnesses.

CHARLES M. GREISING.
